NICHOLAS S. VEDDER, OF TROY, AND TOBIAS S. HEISTER, OF LANSINGBURG, NEW YORK, ASSIGNEES TO NICHOLAS S. VEDDER.

Design No. 4,242, dated July 19, 1870.

DESIGN FOR STOVE-PLATES.

The Schedule referred to in these Letters Patent and making part of the same

To all whom it may concern:

Be it known that we, NICHOLAS S. VEDDER, of Troy, and TOBIAS S. HEISTER, of Lansingburg, in the county of Rensselaer and State of New York, have jointly invented and produced a certain new and original feature in Designs for Stove-Plates, of which the following is a specification, reference being had to the accompanying photographic representations of two cooking-stoves, each showing the principal distinguishing feature of our invention, which consists of the compound central panel-ornament A, having its various parts shaped and arranged together, and disposed

upon and cast with a stove-plate, so as to appear substantially as shown in and by the aforesaid photographs.

What we claim as our invention and production, and desire to secure by Letters Patent, is—

The compound panel-ornament A, shaped and arranged upon and cast with a stove-plate, substantially as shown.
